UNITED STATES PATENT OFFICE.

JOSEPH S. DUNCAN, OF CHICAGO, ILLINOIS, ASSIGNOR TO ADDRESSOGRAPH COMPANY,
OF CHICAGO, ILLINOIS, A CORPORATION OF ILLINOIS.

PRINTING DEVICE.

1,026,248.

Specification of Letters Patent.

Patented May 14, 1912.

Application filed July 25, 1910. Serial No. 573,591.

To all whom it may concern:

Be it known that I, JOSEPH S. DUNCAN, a citizen of the United States, residing at Chicago, in the county of Cook and State 5 of Illinois, have invented new and useful Improvements in Printing Devices, of which the following is a specification.

This invention relates to that class of printing devices in which a printing plate 10 is carried by a frame and which is adapted to be stored in accordance with a card index system and run through an addressing or other printing machine for taking an impression therefrom.

15 The devices are used principally for printing addresses and are generally employed by those who send out many bills regularly to the same customers, such as gas companies, electric light companies and 20 telephone companies. They are also largely used by publishers and other concerns that have large mailing lists.

When a change in address occurs it is necessary to prepare a new printing plate 25 and it is desirable to reduce the cost of thus maintaining the lists up-to-date by avoiding the necessity of replacing the entire plate. In the case of a telephone company, for example, it may be that a telephone 30 number will be permanently located at a certain address and thus if the subscriber moves away from that address it would be sufficient simply to change the name of the old subscriber for that of a new subscriber 35 without changing the remainder of the printing device. This may occur in many other uses of these printing devices but the example above noted will be sufficient to indicate the purpose of my invention.

40 The object of my invention is to reduce the expense of maintaining a system of printing devices of this general character by providing for the renewal of so much only of the printing device as is necessary 45 when changes occur. And a further object of the invention is to provide a sectional printing plate for a printing device of this character, the sections being readily insertible in and removable from the plate and 50 held in place in the plate by means located and arranged at the outer edges of the plate

so as not to obstruct the face of the printing plate.

In the accompanying drawings illustrating one embodiment of my invention Figure 55 1 is a front view of the invention. Fig. 2 is a bottom edge view. Fig. 3 is a sectional view on the line 3—3 of Fig. 1. Figs. 4 and 5 are detail views of the two sections of the printing plate.

60 The frame 6 is provided at its ends with spacing flanges 7 and at its top and bottom with beads 8 and 9. A card 10 is removably held in place beneath the bead 8 and the lips 11 by a stop 12.

65 The printing plate consists of two sections 13, 14, one arranged alongside of the other and located below the card. In the embodiment of the invention selected for illustration the section 13 is both the main 70 and the permanent section and the section 14 is arranged above the main section and is the renewable section. Obviously the section 13 may be renewed while the section 14 remains permanent and the position of the 75 two sections may be reversed. It is also apparent that if a new section 14 is substituted for that section now in the frame the present section may be used in another frame. In other words, by exchanging sections from various frames it may be possible to maintain a system of address printing devices of this character with changes 80 as they occur and without necessitating the production of any new sections whatever. 85 Thus the expense of maintaining the system will be reduced to a minimum and the time involved in making changes will be similarly reduced.

90 The section 13 is held in place on the frame beneath the bead 9 and the lip 15 by a spring catch 16, or other suitable means. The section 14 is held in place alongside the section 13 beneath the lips 15, 17 and 18 and is secured against endwise movement by a projection 19 on the section 13 which enters a notch 20 in the section 14. In inserting the sections in the frame the section 14 will be slid into place sidewise 95 after which the section 13 is slid into place 100 endwise.

It is desirable to have the section 14 of

greater width than is absolutely necessary for the line of type thereon so that the lips 17 may clear the inking device and other parts of the addressing machine. For this 5 purpose the section 14 is provided with projections 21 arranged on its opposite edges in staggered relation to each other. These projections increase the maximum width of the section 14 and they are arranged at one edge 10 so as to engage the lips 17 which, by reason of the projections, are disposed a sufficient distance from the line of type to be clear of the mechanism of the addressing machine. The sections 14 can be stamped out of a 15 sheet of metal without loss of metal for the projections on one side edge lie opposite complementary recesses on the other side edge.

My invention is simple in character and 20 yet it is particularly important for users of printing devices of this character in certain lines of business, particularly where numerous changes in addresses are occurring from time to time. It will be readily perceived 25 that in a case of a telephone company, where subscribers are moving from place to place in the same territory, the necessity for making new plates will be reduced to a minimum because the sections can be interchanged 30 readily and easily to maintain the system up-to-date.

While I have shown the name on the renewable section and the address on the permanent section, this arrangement can obviously be varied in many ways.

What I claim and desire to secure by Letters Patent is:

1. A printing device comprising a frame provided with integral plate retaining means 40 projecting from the plane thereof, and a printing plate consisting of a plurality of detachable sections disposed side by side flat against the frame, each printing plate section being engaged by said retaining means, 45 one of said sections when in position serving to prevent both lateral and longitudinal movement of the other section.

2. A printing plate comprising a frame provided with integral plate retaining means 50 projecting from the plane thereof, and a sectional printing plate, each section lying flat against the frame and engaged by said plate retaining means, adjacent sections of said plate being provided with interengaging means whereby one of said sections maintains the other against longitudinal displacement.

3. A printing device comprising a frame provided with integral plate retaining means 60 projecting from the plane thereof, and a printing plate consisting of a plurality of detachable sections lying flat against the frame and engaged by said retaining means, the adjacent edges of said sections 65 being provided, respectively, with a notch

and a projection adapted to engage therewith, whereby longitudinal displacement of one of said sections is prevented by the other section.

4. A printing device comprising a frame 70 and an address printing plate divided longitudinally into two sections, one of said sections having projections arranged in staggered relation on its side edges, and means for securing said sections in the frame one 75 above and alongside the other, a portion of said means engaging with the projections on the edge of one of said sections whereby the printing face of said section is spaced from said securing means.

5. A printing device of the character described comprising a frame having spaced printing plate retaining means, and an address printing plate made up of sections disposed in mutual edge engagement, the meeting edge of one section being continuous, and the meeting edge of the other section having edge projections engaging the continuous edge of the first-mentioned section, the outer edge of each section being 80 engaged by the adjacent printing plate retaining means, means to prevent endwise displacement of the plates in one direction, a spring locking device to prevent endwise displacement in the opposite direction of the 85 printing plate section having the continuous meeting edge, and an interengagement between the two plates to prevent endwise displacement of the plate having edge projections, the printing plate section having 90 the projections and the opposite printing plate retaining means co-operatively forming a guideway for the endwise insertion and removal of the printing plate section having the continuous meeting edge. 95

6. A printing device comprising a frame having spaced printing plate retaining means, and an address printing plate made up of sections disposed in mutual edge engagement, the meeting edge of one section being continuous and the meeting edge of the other section having edge projections engaging the continuous edge of the first mentioned section, the outer edge of each printing plate section engaging one of the 100 printing plate retaining means, one of the printing plate sections and the opposite printing plate retaining means co-operatively forming a guideway for the endwise insertion and removal of the other printing plate 105 section.

7. A printing device comprising a frame having spaced printing plate retaining means, and an address printing plate made up of sections disposed in mutual edge engagement, the meeting edge of one section being continuous, the other section being provided with transverse projections upon opposite edges, the projections at the inner edge of said plate engaging the meeting 115 120 125 130

edge of the first mentioned plate, and the
projections at the other edge of said other
plate engaging the adjacent printing plate
retaining means, the printing plate section
5 having the projections and the opposite
printing plate retaining means coöperatively
forming a guideway for the insertion and

removal of the printing plate section having
the continuous meeting edge.
